UNITED STATES PATENT OFFICE.

WILLIAM M. PUGH, OF POCOHONTAS, VIRGINIA.

RAIL-JOINT.

1,093,727.

Specification of Letters Patent. Patented Apr. 21, 1914.

Application filed September 29, 1913. Serial No. 792,343.

To all whom it may concern:

Be it known that I, WILLIAM M. PUGH, a citizen of the United States, and a resident of Pocahontas, county of Tazewell, State of Virginia, have invented certain new and useful Improvements in Rail-Joints, of which the following is a full and clear specification, reference being had to the accompanying drawings, in which—

10 Figure 1 is a side elevation of a rail joint provided with my invention; and Figs. 2 and 3 are transverse vertical sections taken through different parts of the rail joint.

15 The object of this invention is to provide a simple nut locking device which will at the same time serve as a means for preventing the projecting ends of the joint bolts from being struck and thus cut off or broken by the wheel flanges should the train vehicle leave the rails, as more fully hereinafter set forth.

20 The usual fish plates *a* and the usual joint bolts *b* are employed. Clamped to the face of one of the fish plates by the usual nuts *c* is a plate *d* and carried by this plate *d* is a plurality of short bolts *e* whose threaded ends project outwardly at points between the joint bolts. A nut locking bar *f* is clamped to the face of the plate *d* by 25 means of the bolts *e* and nuts *g* thereon. This bar *f* is provided with notches which fit over the bolts and serve to prevent them from being rotated in either direction while the locking bar is in place.

30 Along the upper edge of the bar *f* is formed a flange *h* which projects outwardly far enough to protect the projecting ends of

the joint bolts *b*, each end of this flange *h* being beveled off at *i*. With this construction, it will be observed that should the 40 train vehicle leave the rails, the flange *h* will guide or throw the wheel flanges away from the projecting ends of the bolts *b* and thus prevent the wheel flanges from striking the bolts. It has frequently occurred in 45 train wrecks that the damage was greatly increased by the disrupting of the rail joints by the wheel flanges striking against the projecting ends of the bolts and breaking the bolts. This invention completely obviates the possibility of this occurring, 50 while, at the same time, the nuts are locked against being accidentally loosened.

Having thus described my invention, what I claim is—

55 In combination with a rail joint embodying the usual fish plates and bolts and nuts, of a plate *d* clamped by the aforesaid nuts against the adjacent face of the fish plate, a bar *f* and supplemental bolts for removably clamping the same against the face of said plate *d*, this bar being provided with portions which depend between the nuts on the joint bolts and also being provided along its upper edge above said nuts with a longitudinal flange beveled at each end and projecting outwardly beyond the nuts, for the purposes set forth.

60 In testimony whereof I hereunto affix my signature in the presence of two witnesses.

WILLIAM M. PUGH.
